TAPE CARTRIDGE HOLDER FOR AUTOMOBILE CEILING

Albert A. Uriel, 1410 Morrison Road,
Canon City, Colo. 81212

Filed Sept. 27, 1973, Ser. No. 401,368

Term of patent 14 years

Int. Cl. D3—02

U.S. Cl. D87—1 D

FIG. 1

FIG. 2

FIG. 3

FIG. 4

FIG. 5

FIG. 6

FIG. 1 is a front elevational view of a tape cartridge holder for automobile ceiling showing my new design;

FIG. 2 is a top plan view;

FIG. 3 is a rear elevational view;

FIG. 4 is a bottom plan view;

FIG. 5 is a left side elevational view; and

FIG. 6 is a right side elevational view.

I claim:

The ornamental design for a tape cartridge holder for automobile ceiling, as shown.
